UNITED STATES PATENT OFFICE.

ROY EMERY, OF BROOKLYN, NEW YORK.

MOLD ELEMENT FOR CASTING JUSTIFIED LINES OF SINGLE TYPE, LOGO-TYPES, WORDS, DIVIDED SLUGS, AND TYPE BARS.

Application filed September 14, 1922. Serial No. 588,281.

My invention relates to typographical machines, such as linotype machines of the general organization represented in Letters Patent of the United States, to O. Mergenthaler, No. 436,532, wherein circulating matrices are released from a magazine in the order in which their characters are to appear in print and then assembled in line, the composed line transferred to the face of a slotted mold, the mold filled with molten metal to form a slug or line of type against the matrices which produces the type-characters thereon, and the matrices thereafter returned through distributing mechanism to the magazine from which they started.

This invention has for its object to provide a type of matrices for use in machines of the character above described whereby it may be possible to set individual type-characters and spaces and units for space justifying with this class of machines without materially changing the form of the machine as now in ordinary use.

A further object is to make it possible to cast individual type characters and spacing units, separate one from another, excepting that all are connected to slug when cast, by a small web of metal which can be easily removed from the type, leaving the individual type-characters and spacing and justifying members forming a line that will justify into a line of a given length, thus making it possible to make corrections in the product of linotype machines by inserting single characters or words in the place of the incorrect characters or words without the necessity of resetting an entire line of type.

With these and other objects in view reference may be had to the accompanying drawings forming a part of this specification, in which

Figure 1 is a side view of one of the matrices with a small part of the molding mechanism indicated. The casting chamber of the matrix is indicated in dotted lines, and a part of the matrix-wall is broken away to disclose the type; Fig. 2 is an edge view of the matrix shown in Fig. 1; Fig. 3 is of the reverse of that shown in Fig. 1; Fig. 4 is an enlarged perspective view of the matrix; Fig. 5 is an elevational view of a number of the matrices assembled in relation for casting with two spacing matrices therewith;

Fig. 6 is a sectional view taken on the line 55 6—6 looking in the direction of the arrows, excepting that the position of the wedges in the spacing matrices is merely indicated by dotted lines, instead of the construction being shown in section; Fig. 7 is a perspective view of the type product cast from the matrices shown in Figs. 5 and 6; Fig. 8 is one of the matrices for casting spaces and for justifying spaces adapted for use with the character matrix shown in Figs. 1 to 6; 60 Fig. 9 is a side view of the space casting matrix shown in Fig. 8; Fig. 10 is a reverse view of the matrix shown in Fig. 8; Fig. 11 is a reverse view of the adjusting member of the matrix for casting spaces including wedge and is shown obversely in Fig. 10; Fig. 12 is a reverse view of the lug-member of the matrix for casting spaces including wedge and is shown obversely in 65 Fig. 8; Fig. 13 is an enlarged perspective 70 view of the matrix shown in Figs. 8 to 12; Fig. 14 is a horizontal sectional view taken on the line xiv—xiv of Fig. 8; Fig. 15, Sheet 1, is a longitudinal sectional view taken on the line xvi—xvi of Fig. 1 indicating a form of construction of the character matrix; Fig. 16 is a view of a modified form of the space casting matrix; Fig. 17 is a side view of the form of the matrix shown in 75 Fig. 16; Fig. 18 is a reverse view of the matrix shown in Fig. 16; Fig. 19 is reverse view of the adjusting member of the matrix shown in Figs. 16 to 18 and shown obversely in Fig. 18; Fig. 20 is a reverse view of the lug-member of the matrix shown in Figs. 16 80 to 18 and shown obversely in Fig. 16; Fig. 21 is a perspective view of the modified form of matrix shown in Figs. 16 to 20, 85 inclusive; Fig. 22 is a detail view showing the construction of the wedge in spacer. Fig. 23 is a sectional view taken on the line 90 xxi—xxi of Fig. 16; Fig. 24 is a view of a Janus-faced matrix in which a form of casting mold is indicated wherein the slug is connected with the type at the foot instead of at the body portion thereof; Fig. 25 is a view of one edge of the matrix shown in Fig. 24; Fig. 26 is a sectional view taken on the line xxi—xxi of Fig. 24; Fig. 27 95 is an enlarged perspective view of a further modification of the space casting matrix whereby a character can be cast upon a space of a variable width, and of a length 100 105

adapted for printing with the type; Fig. 28 is an enlarged perspective view of a still further modification of the space casting matrix, and Fig. 29 is an isometric perspective of the type product from my character matrices used with the form of space casting matrix shown in Fig. 27, with the exception that in this figure the spaces are indicated as cast without any character thereon. The slug is connected at the foot of the type. Fig. 30 is an enlarged perspective of a modified form of spacing matrix. Fig. 31 is an end elevational view of the type product shown in Fig. 7.

In the practice of my invention matrices are used substantially the same as those ordinarily used in linotype machines, but certain modifications are as follows:

Instead of casting in a matrix provided in the edge 11 of the matrix 10 as in ordinary practice, I provide a shoulder 12 over a recess 13 in the edge of the matrix, and the character from which the type character is cast, "F" is formed in the under surface of the said shoulder 12. The edge wall 11 forms one side of the type-body as 14, the body of the matrix as at 10^a forms the rear surface of the type and the adjacent edge wall of the adjoining matrix forms a third surface of the type, and the mold forms the foot and front of the type-body.

Referring to Fig. 1, a type-body 14 is indicated (mostly in dotted lines) in the position for casting. 15 indicates the upper member of a molding means; 16 the lower member thereof; 17 indicates a foot-plate which acts in conjunction with the molding members 15 and 16 in positioning the mold and forming the foot of the type. This foot-plate enters the recess of the matrices as 18 and is moved upwardly for the casting operation when it is in the position indicated in Figure 1.

I do not claim this molding means as a part of this invention, but only indicate it in order to illustrate the slight departures such as may be necessary, from mechanism now in use, in the practice of my invention and thus demonstrate the feasibility of my invention.

The matrix may be made from a single piece of material or it may be formed from two superposed plates, in which case the lugs 19 would be provided upon one plate and the recess 13 would be formed in the mating member before assembling the parts of the matrix. In Fig. 15 Sheet 1, is shown a sectional view of one of the matrix formed from two plates, in which A indicates the matrice, A' the member in which the recess is formed, and A² the member on which the lugs are formed, fully illustrated as to form in other views of the drawings.

The edge wall 11 of the recess 13 is notched as at 11^a to admit a bead 20 formed by the

extension as 20 provided on the mold member 16, so when a number of matrices are aligned in the mold, and the molding members are brought into position, and the molten metal forced into the mold, the bead 20 will form a notch in the body of the type corresponding to the notches 11^a in the matrices.

The mold is so constructed that it forms a slug or tang 21 which is connected by a thin web of metal to the type members as 22, (see Fig. 7) and this thin web of metal joins the type body at the upper portion of the notches as 11^a.

By this process of casting single type in a linotype machine I make it possible to set type by a type of machine which is already introduced and at the same time overcome a great objection to line-casting machines; by making it possible to cast single type in a line so that necessary corrections may be made by hand and it is not necessary to cast an entire line to correct a single word or single letter.

To justify a line of type so that when assembled in a line it will produce a justified line of a desired length, I provide a matrix for casting spaces as 23 shown in Figures 8 to 14 and modified forms thereof are shown in other views of the drawings.

The space casting matrix comprises, a wedge 24, the lug-member 25 and the adjusting member 26. The wedge 24 is provided with tongues 24^a and 24^b which extend longitudinally thereof and slide in grooves provided in the lug-member 25, and the adjusting member 26, respectively. The lug member 25 has parallel grooves 25^a and the adjusting member 26 has parallel grooves 26^a therein. The grooves 25^a of the lug-member are in a plane with the body of the lug-member, but the grooves 26^a of the adjusting member, are inclined from the plane at an angle conforming with the inclination of the wedge 24, whereby the lug-member and the adjusting member are relatively moved from one another as the wedge is inserted therebetween and forced inwardly in the direction of the thin point thereof, and "vice-versa", so that when the wedge is withdrawn the parts are in normal position, but when the wedges are forced upwardly the thickness of the matrix and the casting space in the recess thereof is relatively increased.

Both members of the spacing matrix are recessed as at 27 and 28 correspondingly with the matrix for characters as at 18 for admitting the foot-plate 17, and the lug member 25 is notched at 29 to admit the bead 20 of the molding means, correspondingly with the notch 11^a in the edge wall 11^a of the matrix 10.

The adjusting member 26 is recessed as at 30 and a flange member 31 is provided

on the lug-member 25, and fits snugly within the recess 30. When the two members are adjusted closely the edge of the flange-member 31 will be substantially in alignment 5 with the outer surface of the adjusting member 26, but as they move one from another, the flange receding forms a wall at the upper end of the recess and in the base or rear of the recess, so that there can be no 10 open space between the lug-member and the adjusting member, but the flange member serves as an extension wall for the recess 30 of the adjusting member 26. By properly determining the taper of the wedge, and 15 the thickness and dimensions of the members of the matrices any size or thickness of space body can be cast.

When the type matrices are assembled in the mold for casting they are in series, as 20 follows: a wall, a recess, a wall a recess and a matrix holding jaw which forms one side of the end character when space matrices are introduced the same order obtains (see Figs. 5 and 6). Thus the type is formed 25 partly by the matrix which forms the character, but one side is formed by the outer surface of the adjacent matrix. This is true whether the adjacent unit be a space casting matrix or a character matrix. But the body 30 cast in the spacing matrix is shorter than that cast in the character matrix.

To prevent the lug-member from displacement longitudinally relative to the adjusting member, by sliding on the wedge, a pin 32 is set in the lug-member and is disposed through a hole, 33 in the adjusting member. To prevent the wedge from being withdrawn from the members of the spacing matrix by its thin end a stud 34 is set in 40 the wedge near its thick end.

In Figures 16 to 23 I have shown certain modifications of the space casting matrix. The matrix proper 35, is not recessed so deeply at 36, as is the specific form hereinbefore described, said recess extending only to the base of the recess, 37, for casting the type or space-body. The lug-member is provided with an extension 38 which fits within the recess 39 of the adjusting member. 50

The wedge 40 is made with tongues 40^a and 40^b, which are at a spaced distance from the faces 40^c and 40^d of the wedge and corresponding grooves are provided in the members of the matrix. By using this form of the wedge, it is possible to extend the wedge so that its outer surfaces 40^c and 40^d are flush with the exterior of the matrix members or the recess 39 of the adjusting member. The wedge may be made integrally but if desired may be made of superposed members, as 41, 42 and 43 as shown in Fig. 22.

A further modification of the space casting matrix is shown in Fig. 27. In this

form thereto the matrix 44 is the same as the form described in the above and foregoing and shown in Figures 16 to 23 of the drawings, except, that the recess 45 is of a depth to correspond with the recess in the 70 character matrices and the space bodies may be cast as high as the type; and in addition to this, any character, as a period (.) a hyphen (-) a star or any letter or asterisk (*) as 46 may be provided so that the space 75 body may be employed for printing certain characters which are often repeated, or any character desired may be cast in the spacing matrix. Expansible matrices (styled spacing matrices) may be employed for casting 80 any or all characters, on variable bodies.

A still further modification is shown in Figure 28. The upper portion of the matrix 47, is the same as that shown in Figure 27 except that no character is employed in this 85 form, but the shoulder 48 is plain and forms a plain upper end on the space body; and is at the same level as the shoulder 12 in the character matrix; but at the lower portion of the recess, there is an extension 49 on the adjusting member 50, upon which the foot of the space body is cast, and upon which the extension, 51 of the lug member 52, moves when adjustment is made. A 90 perfect space body may be cast in this mold, and at the same time the body will be shorter than the type body and for letter-press printing or other purposes where it is desired to have spaces shorter than the 95 type this meets the requirements.

In Figures 24, 25 and 26 I show a character matrix which will cast two different characters. The matrix 53 has two recesses 54 and 55 with two overhanging shoulders 56 and 57 on opposite sides of the matrix, 100 having characters therein as "6" and "F" respectively. There are now in use various devices for turning or reversing matrices in linotype machines and by use of these it is possible to employ this matrix to a great 105 advantage from an economic standpoint.

In Figure 24 I have shown a mold by which the type is cast from the foot instead of the middle or body-portion of the type.

In Figure 29, I have shown in perspective a slug with a number of characters, viz. "O f t h e t i m e". It is possible to make space between the bodies of the type and the spaces very thin by making the partition walls thin, so that the length of the slug will be but slightly longer than the line in which the type is to be set in the form and justified for printing. This is regulated by the thickness of the wall of the casting recess. If the walls are made very thin the sum of the thickness of the walls plus the space occupied by the type and spaces will be but little greater than the justified line of type.

In Figure 30 I have shown a modified 130

form of a matrix as 58 which is substantially the same as that shown in Figs. 1 to 4 except that it has no side wall to the recess 59, as 11 in Fig. 4 so that an integral unit may 5 be, cast in this matrix and the adjacent matrix. This matrix may be of any desired thickness and with or without a character in the shoulder 60.

While I have specifically described the 10 forms of matrices illustrated in the drawings, I do not wish to be limited thereby but reserve the right to depart therefrom within the spirit and scope of the invention.

Having thus described my invention, 15 what I claim as new therein and desire to secure by Letters Patent of the United States, is:

1. A matrix of the character described having a recess for casting, with a rear wall 20 and one side wall, formed longitudinally in one side of the matrix, a shoulder for forming the top of the unit cast, and a transverse recess for positioning the casting mold, substantially as shown and described.

2. A matrix of the character described having a recess for casting, with a rear wall and one side wall, formed longitudinally in one side of the matrix, a shoulder for forming the top of the unit cast, disposed 30 in the upper part of the recess, and a transverse recess, formed in the lower part of the matrix, for positioning the casting mold, and a recess in the edge of the side wall for forming a notch in the unit cast, substantially as shown and described.

3. A matrix of the character described in combination with a matrix of variable thickness and having a recess for casting, with a rear wall and one side wall, formed longitudinally in one side of the matrix, variable in width according to the variable thickness of the matrix, an element provided at the upper portion of the recess for forming the top of the unit cast, and means for adjusting the variable thickness of the matrix, substantially as shown and described.

4. A matrix of the character described, in combination with a matrix of variable thickness and having a recess for casting 50 parallel with the axis thereof in one side of the matrix and variable in width according to the variable thickness of the matrix, an element provided at the upper portion of the recess for forming the top of the unit cast, means for adjusting the variable thickness of the matrix, means for preventing displacement of casting metal when the matrix is variably adjusted, and means for positioning the casting mold, substantially 60 as shown and described.

5. A matrix of the character described in combination with a matrix of variable thickness and having a recess for casting, formed 65 parallel with the axis of the matrix in one side of the matrix and variable in width ac-

cording to the variable thickness of the matrix, a shoulder formed in the matrix at the upper part thereof for forming the top of the unit cast, a recess in the edge of the side-wall for forming a notch in the unit cast, a transverse recess in the lower part of the matrix for positioning the casting mold.

6. A matrix of the character described in combination with a matrix of variable thickness and having a recess for casting, 70 with a rear wall and one side wall, formed longitudinally in one side of the matrix parallel with the axis thereof and variable in width according to the variable thickness of the matrix, adaptable for casting spaces 80 and justifying spaces and having a shoulder at the upper part of the matrix for forming the top of the unit cast, whereby the spacing units are made lower than character units, means for variably adjusting 85 the thickness of the matrix, means for retaining the relative longitudinal relation of the adjustable members of the matrix, substantially as described and shown and for the purposes set forth.

7. In combination, a matrix of the character described having a recess for casting with a rear wall and one side wall formed longitudinally in one side thereof, a shoulder for forming the top of the unit cast and a transverse recess for positioning the casting mold and an auxiliary matrix having a recess with a rear wall and corresponding with the recesses of the primary matrix but having a shorter casting recess whereby the portion of the unit formed by the auxiliary matrix will terminate at the base of the character formed upon the unit; said matrix being adapted when disposed in line with other matrices for casting individual types 100 as herein described for adding to the thickness of the unit cast in the character matrix adjacent for justifying the type cast in one operation substantially as shown and described.

8. In combination, a matrix of the character described, having a recess for casting with a rear wall and one side wall formed longitudinally in one side of the matrix and parallel with the longitudinal axis thereof, 110 a shoulder for forming the top of the unit cast and a transverse recess for positioning the casting mold; with means for increasing the thickness of a unit cast or for casting blank slugs for justifying, substantially as 120 shown and described.

9. In a matrix of the character described, having a recess in the side thereof, with a rear wall, and a deeper recess for positioning the casting mold, and having a shoulder for 125 forming the top of the unit, substantially as shown and described.

In testimony whereof, I ROY EMERY have signed my name to this specification.

ROY EMERY.
